UNITED STATES PATENT OFFICE.

ROBERT HADDEN, OF ATLANTIC CITY, NEW JERSEY.

DESIGN FOR AN ANTISIPHON TRAP-FIXTURE.

44,404.

Specification for Design.

Patented July 29, 1913.

Application filed May 15, 1913. Serial No. 767,924. Term of patent 7 years.

To all whom it may concern:

Be it known that I, ROBERT HADDEN, a citizen of the United States, and a resident of Atlantic City, Atlantic county, New Jersey, have invented a new, original, and ornamental Design for Antisiphon Trap - Fixtures, of which the following is a specification, reference being had to the accompanying drawing, forming part thereof, in which—

Figure 1, is an edge view of the design;

Fig. 2 is a side elevation of the same, and Fig. 3, is a plan view thereof.

I claim:

The ornamental design for an anti-siphon trap fixture, as shown.

ROBERT HADDEN.

Witnesses:

Wm. I. ROLST,
A. WEINTROB.
